UNITED STATES PATENT OFFICE.

ELIZABETH FRIES, OF ST. LOUIS, MISSOURI.

MOP.

1,104,979.

Specification of Letters Patent. Patented July 28, 1914.

Application filed February 28, 1914. Serial No. 821,825.

To all whom it may concern:

Be it known that I, ELIZABETH FRIES, a citizen of the United States, and resident of St. Louis, Missouri, have invented certain new and useful Improvements in Mops, of which the following is a specification containing a full, clear, and exact description, reference being had to the accompanying drawings, forming a part hereof.

- 10 My invention relates to an improved mop, and consists in the novel construction and arrangement of parts hereinafter described and specifically designated in the appended claims.
- 15 The object of my invention is to provide an improved mop, which shall have a narrow front finger and two lateral fingers which can be inserted in narrow crevices to clean the same.

- 20 A further object is to provide an improved mop which shall be of low cost and high efficiency.

In the drawings: Figure 1 is a side elevation of a mop embodying my invention; Fig. 2 is a top plan view of the skeleton mop frame; and Fig. 3 is a sectional side elevation of my improved mop.

In carrying out my invention, I first provide a metallic skeleton frame which has a diamond shaped body 1 and a narrow front integral finger 2 located on the forward side of said diamond shaped body and a rear handle finger 3 all formed integral, of wire, or a metallic rod of suitable size to make the frame sufficiently strong and durable.

The lateral sides of said diamond shaped body 1 form V-shaped fingers 4, which are adapted to be inserted in small spaces to be cleaned.

- 40 The front finger 2 and the handle finger 3 are formed by doubling the metallic rod

upon itself so that said double portions extend parallel as shown. The rear ends of the portions of said handle finger 3 are provided with integral eyes 5, through which 45 passes a suitable bolt or rivet 6 used in pivotally connecting the lower end of the handle 7 to the said eyes. The said handle 7 is preferably provided upon its lower end with a suitable metallic socket 8, through a perforation in which the said bolt 6 is passed.

The frame of the mop as above described, is covered with suitable mop material 9, which is bound on its upper edge by a strip 10 of cloth or other suitable material, and 55 this cloth is made to embrace the said mop frame as shown, and is stitched to the said mop material.

I claim:

1. The improved mop, having a diamond-shaped metallic rod frame formed of a rod doubled upon itself to form a narrow front finger, integral lateral fingers extending from said frame and integral parallel portions at the rear of the frame forming a 65 handle finger, and a suitable handle applied to said handle finger.

2. The improved mop, comprising a metallic rod frame having a diamond shaped body adapted to support mop material, a 70 narrow front finger connected to the front portion of said body, a narrow handle finger connected to the rear portion of said body, and a suitable handle applied to said handle finger.

In testimony whereof, I have signed my name to this specification, in presence of two subscribing witnesses.

ELIZABETH FRIES.

Witnesses:

E. L. WALLACE,
JOHN C. HIGDON.
